UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, COPARTNERS, TRADING AS JOHN BROMLEY & SONS, OF PHILADELPHIA, PENNSYLVANIA.

DESIGN FOR A RUG.

SPECIFICATION forming part of Design No. 36,776, dated February 2, 1904.

Application filed November 25, 1903. Serial No. 182,690. Term of patent 3½ years.

To all whom it may concern:

Be it known that I, ADOLPH PETZOLD, a citizen of the United States, residing in the city of Philadelphia, State of Pennsylvania, have

5 invented a certain new, original, and ornamental Design for a Rug, of which the following is a specification, reference being had to the accompanying drawing, forming a part thereof.

10 The design therein represented relates to

the surface ornamentation of a woven rug, and the drawing represents one half of the design, the other half (not shown) being a duplicate thereof.

I claim—

15 The ornamental design for a rug, as shown.

ADOLPH PETZOLD.
